Arthur S. Parks, Sandwich, and Bruce Chandler,
Waukegan, Ill., assignors to Sandwich R. V.
Pump Co., a corporation of Illinois

Application July 31, 1948, Serial No. 147,866

Term of patent 14 years

(Cl. D65—1)

To all whom it may concern:

Be it known that we, Arthur S. Parks and Bruce Chandler, citizens of the United States, residing at Sandwich, in the county of De Kalb and State of Illinois, and Waukegan, in the county of Lake and State of Illinois, respectively, have invented a new, original, and ornamental Design for a Vacuum Pump Unit, of which the following is a specification, reference being had to the accompanying drawing, forming part thereof.

Figure 1 is a front elevational view of a vacuum pump unit embodying our new design;

Figure 2 is a side elevational view of the vacuum pump shown in Fig. 1; and

Figure 3 is a top plan view of the vacuum pump.

The dominant features of our design reside in the vacuum pump shown in full lines.

We claim:

The ornamental design for a vacuum pump unit, as shown and described.

ARTHUR S. PARKS.
BRUCE CHANDLER.
